UNITED STATES PATENT OFFICE.

GAETANO MELLINO, OF NEW YORK, N. Y.

CAR-FENDER.

1,068,913.

Specification of Letters Patent.

Patented July 29, 1913.

Application filed November 30, 1912. Serial No. 734,299.

To all whom it may concern:

Be it known that I, GAETANO MELLINO, a subject of the King of Italy, and a resident of the city of New York, borough of Manhattan, in the county and State of New York, have invented a new and Improved Car-Fender, of which the following is a full, clear, and exact description.

Among the principal objects which the present invention has in view are: to provide a fender, the operation of which insures the lifting of a body from the ground when directly in front of the vehicle to which the fender is applied; to provide means whereby the body is deflected laterally from the path of said vehicle and away from the carrying wheels thereof; to provide means whereby relatively permanent deflecting members are arranged to accommodate inequalities in the roadbed, and are provided with means operable, on emergency, for closing the gap between the roadbed and the body of the deflector; and to provide means automatically operable for placing the fender in lowered position and for closing the gap between the side deflectors and the roadbed.

Figure 1 is a perspective view of a street car of conventional construction, having applied thereto a fender constructed and arranged in accordance with the present invention; Fig. 2 is a horizontal view of the forward segment of a car so constructed, and provided with a fender constructed and arranged in accordance with the present invention; Fig. 3 is a detail view, on an enlarged scale, taken on the line 3—3 in Fig. 1, showing one of the side fender boards, the gap closure strip therefor, and means for operating the latter; Fig. 4 is a horizontal section taken on the line 4—4 in Fig. 5, showing an end scoop and means for operating the side board closure strips; Fig. 5 is a detail view taken on the line 5—5 in Fig. 4; Fig. 6 is a side view of an end fender, together with the side boards and closure strips therefor, the latter being shown in released or operating position; Fig. 7 is a view showing the inner side of a side board and closure strip therefor, together with means for operating said strip; Fig. 8 is a horizontal section taken on the line 8—8 in Fig. 7; Fig. 9 is a detail view, on an enlarged scale, taken on the line 5—5 in Fig. 4, showing the forward edge of the scoop apron as held in raised or normal position.

As shown in the accompanying drawings,

the invention is applied to a street car of conventional construction. The design, however, is slightly modified to form at the under side of the dash, an arch 13. This arch is provided to give access to a scoop formed by an apron 14, a back 15 and fixed cheek pieces or rigid side frames 16, as best seen in Fig. 1 of the drawings.

The apron 14 is provided with a rectangular frame 17, which is hinged to the bottom rail of the frame 18 of the back 15. The front rail 19 of the frame 17 is shaped to slide on the roadbed when dropped thereto, and is provided midway of the rail with a boss 20, having formed therein an inwardly-opening socket to receive the end of a supporting latch hook 21.

The body of the apron is constructed of any suitable resilient material, that shown in the drawings being a woven wire mesh, which is preferred. The cushioning effect of the wire mesh of the apron 14 is supplemented by the cushioning effect of the wire gauze which is stretched between and mounted upon the frame 18, forming therewith the back 15. Normally, the apron 14 is supported by the latch hook 21, the front rail 19 of the apron being lifted free of the roadbed on which the car travels. The latch hook 21 is pivoted in vertical bearings formed in a clip 22 at the back of one of the fender bars 23. The fender bars 23 are pivotally mounted by means of hinges 24, upon the cheek pieces 16, which cheek pieces are rigidly mounted upon the body of the car. The bars 23, when closed, are positioned in front of the rail 19. In this position the hook of the latch 21 fits within the socket formed in the boss 20. This is the normal position of the apron 14.

To accelerate the drop of the front rail 19 to the bed of the road, and to maintain the same in contact therewith, I provide spiral springs 25. These springs infold rods 27, which are hinged at 26 upon the frame 17, and extend through perforations in the back frame 18. The springs 25 bear against the sides of the frame 18, and normally press downward the apron and the forward rail 19 thereof.

When, the parts being in the position just above described, a body lying on the roadbed is struck by the fender-bars 23, these yield backward, and carry the latch hook 21 out of engagement with the boss 20. The springs 25 instantly depress the front rail

19 upon the roadbed in time to extend beneath the body which lies thereon. The body, being thus lifted, rolls backward over the apron 14, and is arrested by striking 5 upon the back 15. The yielding material of which both the apron and back are constructed softens the blow imparted to the body, which otherwise might be severe.

After the body has been removed from 10 the apron, and when the car is stopped, the apron is again lifted, the springs 25 being compressed, until the socket in the boss 20 registers with the latch hook 21, when the fender bars 23 are disposed in operative 15 position. The pressure of the springs 25 upon the apron 14 holds the fender bars 23 in locked position, to prevent the vibration of the car from releasing the same.

It is to prevent the intrusion of a body 20 under the overhanging sides of the car that I have provided the side boards 28. The side boards 28 are mounted upon the car structure by means of hinges 29. Each of the side boards 28 is provided with a hinge 25 strip 30, which normally coincides with the side of the car structure, and is connected to the main portion of the board 28 by means of a wedge-shaped offset piece 31. At each side of the car, there are two side 30 boards 28. The widened ends of the offset pieces 31 abut at the middle of the car structure. The greatest width of the pieces 31 determines the offset of the side boards 28 from the car structure, which, as seen 35 best in Fig. 1 of the drawings, is at the longitudinal median section of the car structure. The purpose of the side boards 28 is to deflect any body struck thereby, outward from the car body, and to deliver the 40 same away from the car body at approximately the longitudinal median section thereof. The side boards 28 are hinged to the car structure, to permit the same being lifted when it becomes necessary to inspect, 45 or gain access to the trucks or running gear of the car.

The normal position of the side boards is substantially as shown in Fig. 1 of the drawings, and the lower edge thereof is raised 50 above the roadbed at the outer side of the rails thereof, to accommodate the swing of the car body when the car is moving, or when the car is passing around a curve, the rails being banked, as is the usual custom. 55 It is to close the gap between the ground and the lower edge of the side boards 28 thus provided, that each side board is provided with a drop board 32. The drop board 32 is guided in grooves formed by 60 the overhanging rails 33, with which each of the side boards 28 is provided (see Fig. 7 of the drawings).

Normally, the drop boards are raised, the lower edge of said drop boards coinciding 65 with the lower edge of the side boards 28.

To suspend the drop boards 32, cables 34 are furnished, which cables are attached to the drop board by means of perforations extended through the bracket 35 with which each of said drop boards is provided. The 70 normal position of each of the drop boards 32 is inside the side board 28 upon which it is mounted. The cables 32 are therefore strong at the outer side of the side boards, as seen in Fig. 1 of the drawings. At the 75 forward end of each of the side boards, the double cable 34 is threaded through an eyelet 36, and is provided with a ring 37, which is normally engaged by a latch hook 38. The hooks 38 are pivotally mounted in bearings formed in the bracket 39, and are each provided with a hook section adjacent the ring 37, and with a curved tailpiece 40. The two tailpieces 40 normally rest inside of presser-feet 41, with which each of the edge 80 gates 42 is provided. The gates 42 are hinged upon the outer vertical edge of the cheek pieces 16, and are flared outwardly therefrom, as shown best in Figs. 2 and 4 of the drawings. When, now, a body which 85 is prone on the roadbed and at the side of the path of the apron 14, is struck by one of the gates 42, said gate is swung on its hinge, carrying the presser-foot 41 therewith and the tailpiece 40, rocking the latch 90 hook 38 until it releases the ring 37 and cable 34 connected therewith. When the ring and cable above mentioned are thus released, a spring 43 bears downward upon the drop board 32, to lower the same in contact with 95 the ground, and to close the gap under the side board 28. The person or body is now deflected laterally from the side board and drop board connected therewith, outward from the body of the car. This operation 100 prevents the person or body from passing under the wheels of the car or the structure connected therewith, such as the journal boxes. When the body has been thus saved from mutilation and deflected out of harm's 105 way, the drop board 32 is again raised into operative position by the attendant drawing upon the ring 37, and locking the same in its drawn position by means of the latch hook 38. The gate 42 is then set in operative 110 or normal position.

Having thus described my invention, I claim as new and desire to secure by Letters Patent:—

1. A car fender having a scoop adapted 120 to swing in contact with the roadbed when moved thereto, in combination with a plurality of side boards flared outwardly at the rear of said scoop, to deflect a body outward from the side of the car having said fender; and pivoted yielding means mounted on said scoop at the forward side edges thereof, to close the space between the bottom of said side boards and the roadbed.

2. A car fender having a scoop adapted 125

- to swing in contact with the roadbed when moved thereto, in combination with a plurality of side boards flared outwardly at the rear of said scoop, to deflect a body outward from the side of the car having said fender; and a plurality of movable drop boards mounted upon said side boards to close the space between the lower edge of said side boards and the roadbed, when moved thereto.
3. A car fender having a scoop adapted to swing in contact with the roadbed when moved thereto, in combination with a plurality of side boards flared outwardly at the rear of said scoop, to deflect a body outward from the side of the car having said fender; a plurality of movable drop boards mounted upon said side boards to close the space between the lower edge of said side boards and the roadbed, when moved thereto; and yielding means disposed in front of said scoop to release said drop boards.
4. A car fender having a scoop adapted to swing in contact with the roadbed when moved thereto, in combination with a plurality of side boards flared outwardly at the rear of said scoop, to deflect a body outward from the side of the car having said fender; pivoted yielding means mounted on said scoop at the forward side edges thereof adapted to close the space between the bottom of said side boards and the roadbed; and a plurality of drop boards suspended on said side boards and operatively connect-
- ed with said yielding means, to be disposed thereby to close the space between the edge of said side boards and the roadbed.
5. A car fender such as described, comprising a yielding back member vertically and permanently mounted on a car; a bottom pivotally mounted upon said back member; relatively rigid side frames extending in front of said bottom; a plurality of fender bar sections pivotally mounted on said side frames; and a latch hook mounted on one of said fender bar sections to normally support in raised position the free end of said bottom.
6. A car fender such as described, comprising a yielding back member vertically and permanently mounted on a car; a bottom pivotally mounted upon said back member; relatively rigid side frames extending in front of said bottom; a plurality of fender bar sections pivotally mounted on said side frames; a latch hook mounted on one of said fender bar sections to normally support in raised position the free end of said bottom; and a plurality of springs mounted upon said back and said bottom to operate to depress the forward end of said bottom.

In testimony whereof I have signed my name to this specification in the presence of two subscribing witnesses.

GAETANO MELLINO.
